Application May 11, 1939, Serial No. 273,027

9 Claims. (Cl. 93—36)

This invention relates to the manufacture of paper containers by automatic machinery. The machine hereinafter described provides for applying a reenforcing tab or patch in precise register on a container blank, and thereafter folding and gluing the blank to furnish a container in flat folded condition. The tabbing unit of this machine provides for cutting and punching individual tabs or patches from a web drawn from a supply roll, and thereafter delivering the tabs singly and successively in timed relation upon predetermined adhesively treated areas of container blanks. Containers of the type produced by this method and machine are used for packaging liquids, powders and any other commodity which requires a sealed closure which may be easily opened. My improved method and machine are adaptable for use wherever a tab or patch is required to be applied to a sheet of material in close register.

One of the objects of my invention is to effect rapid production of paper containers in flat folded condition with a reenforcing tab secured thereto.

Another object of my invention is to provide a tabbing mechanism which will apply tabs, in precise register, to paper blanks at high speed by automatic machinery.

Still another object of my invention is to provide a method and machine for making cut and scored tabs from a web of material, and thereafter applying the tabs to predetermined sections of moving box blanks.

Other more specific objects and advantages of the invention will be apparent to persons skilled in the art as the same becomes better understood by reference to the following description, taken in connection with the accompanying drawings, in which I have illustrated one practical embodiment of the invention, and wherein:

Figure 1 is a side elevation of my improved machine, with part of the frame and folding members broken away.

Figure 2 is a plan view of Figure 1.

Figure 3 is a partial section at 3—3 of Figure 2.

Figure 4 is a partial section at 4—4 of Figure 2, showing the punching and cutting mechanism out of contact with the tab supplying web.

Figure 5 is a partial section at 5—5 of Figure 2.

Figure 6 is a partial section at 6—6 of Figure 2.

Figure 7 represents a plan view of the cut and

scored blank from which the body of the container is formed.

Figure 8 is a plan view of the blank showing the adhesively treated area provided for securing the tab to the blank.

Figure 9 is a plan view of the blank showing the tab secured in position upon the blank.

Figure 10 is a plan view showing the blank in partly folded condition, with the adhesively treated surface of connection flap e facing upwards.

Figure 11 is a plan view of the container in flat folded condition, after the wall folding operation has been completed.

Figure 12 is a plan view of the tab which forms part of the container closure when secured to the body of the blank.

Figure 13 is a view showing the container opened to tubular form.

Figure 14 is an end view of Figure 13.

Figure 15 is a perspective view of the completed container in set-up condition.

Figure 16 illustrates the tab supplying web after it has been operated on by the shearing punch, and scoring knife.

It will aid toward an understanding of the operation of the machine and of the method of fabricating the container, to first explain the action of the machine which effects the production of containers in flat folded condition from cut and scored blanks. Figure 7 illustrates a cut and creased blank, wherein creased lines are indicated by dash lines marked s, r, y, y¹, z and z¹. Said creased lines effect a division of the blank to form side walls a, b, c, and d, a connection flap e, flap extensions l and m, and bottom closure members f, g, h, and k. The top closure members comprise sections marked n, o, p, and q. A cut-out u and scored lines v are provided in the top closure member p. The scored lines v provide a flap element t in said closure member p. Figure 8 illustrates the condition of the blank after it has been acted upon by adhesive applying mechanism which applies adhesive to the closure member p for the purpose of securing the reenforcing tab w (Fig. 12) thereto. Figure 9 shows the condition of the blank after the reenforcing tab w has been secured in place. The reenforcing tab (Fig. 12) is provided with a U-shaped cut x, and a scored line x¹. After the tab w has been secured in place, the blank is conveyed forward and in so moving passes over a glue wheel which operates to apply a stripe of adhesive to the underside of flap connection e (Fig. 9). Figure 10 illustrates

45

40

the condition of the blank after side wall *a* has been folded on creased line *y*1 to overlie side wall *b*. Side wall *d* is then folded on creased line *z*2 with the result that the free edge of side wall *d* will contact the adhesively treated flap connection *e* and become secured thereto; the blank is then in the condition illustrated by Figure 11.

Referring to Figures 1 and 2, these two figures illustrate respectively, an elevation view, and a plan view of the entire machine. The base of the machine consists of a frame 1 provided with suitable bearings and brackets for attaching the different mechanisms thereto. Box blanks which have been shaped, creased and cut, as shown in Figure 7 and more fully described above, may be cut and creased by any of the well known methods in common use in the art. In the operation of the machine, box blanks of the type above described are delivered singly and successively from a stack on feed table 2 to the conveyor belt 3. The conveyor belt is supported and driven by rolls 4 and 5 journaled in frame 1. Roll 12 secured to shaft 14 journaled in frame 1 serves to support the midsection of the upper strand of the conveyor belt. The said conveyor belt 3 operates to advance the blanks to pass under adhesive applying roll 7 secured to shaft 8 journaled in frame 1. The adhesive applying pad 9 secured to adhesive applying roll 7 is cut to the pattern of the area of the blank to be adhesively treated. Adhesive is applied to said pad 9 by contact with the adhesively coated roll 13 to which liquid adhesive is carried by roll 11 which is caused to rotate in liquid adhesive contained in reservoir 10 supported by frame 1. Said rolls 11 and 13 are journaled in reservoir 10.

The blank is next carried forward to the tab cutting and tab applying unit which operates to make and apply a tab *w* (Fig. 12) to the previously adhesively treated area of closure member *p* (Fig. 8). The said tabs *w* are cut singly and successively from a web fed from a roll of paper stock 15 supported by shaft 16 journaled in frame 1 (Figs. 1, 3 and 4). From the tab supplying roll 15 the web passes under guide roll 17 secured to shaft 18 journaled in frame 1. Thence the web passes to the tab punching, cutting, and scoring mechanism. The punch 33 is positioned under the web and supported by bracket 29 secured to frame 1. The bolster carriage 37 is caused to operate up and down by shaft 38 which is secured thereto. The said bolster carriage is guided by bars 39 supported by frame 1. Two connecting links 44 each having its upper end operatively secured to an end of said shaft 38; the lower end of each connecting link being operatively secured to eccentric shaft 42 which is journaled in frame 1 (Fig. 5). Eccentric shaft 42 is driven by pulley 43 secured to one end thereof. It is obvious that the rotation of eccentric shaft 42 will impart an up and down motion to bolster carriage 37; connecting links 44 and shaft 38 serving to couple said bolster carriage with the eccentric shaft. Bolster plate 34 secured to the under side of bolster carriage 37 is provided with a scoring knife 35, a cut-off knife 36, and a die recess 40. Figure 4 shows the bolster carriage 37 in raised position out of engagement with the web, while Figure 3 shows the said bolster carriage 37 in contact with the web. Figure 16 illustrates a section of the web after the cutting, punching and scoring operation has been performed. It will be obvious that with each operation of the bolster carriage 37, differ-

ent operations are performed on three tab sections of the web. In other words, while cutting knife 36 is severing a completed tab from the web, the punching operation is taking place on the next succeeding tab and a scored line *x*1 (Fig. 16) is being impressed in a third tab section. After the bolster carriage 37 has been raised out of contact with the web, the stripping pins 30, slidably secured in bracket 29, operate to lift the web out of contact with the punch 33. The compression springs 32 operate to maintain the pins 30 in raised position, except when the bolster plate 34 forces the said pins downward during the dieing operation. The shoulders 31 on pins 30 serve to limit the upward motion of said pins.

From the punching, cutting, and scoring unit the prepared tabs pass to the tab applying wheel 22, which rotates in timed relation with the cutting and scoring mechanism and with the roll 19 secured to shaft 20 journaled in side frame 1. Secured to said roll 19 is a striker pad 21 made of any suitable material such as leather, wood or rubber. The tabs, as they are advanced, are gripped between wheel 22 and pad 21. The prongs of forks 24 which are slidably secured within wheel 22 operate to dig into the forward end of the tabs and carry them in timed relation to register on the adhesively treated areas of the container blanks as they pass under wheel 22. The prongs of forks 24 are arranged to pierce the forward end of each tab as it comes from the cutting and scoring unit and serve to hold the tab in engagement with wheel 22 which carries the tab through a semi-circular path to its position on the container blank. When each tab reaches the register point on the container blank, the prongs of forks 24 carrying the tab are withdrawn from the periphery of the wheel 22 by means of compression spring 26 co-operating with cam recess 25 (Figs. 3 and 6) cupped in stationary shaft 23 secured in frame 1. The wheel 22 (Fig. 6) is rotatably mounted on shaft 23 and driven by pulley 48; dowel pin 49 serves to secure wheel 22 and pulley 48 together. Dowel pin 50 serves to maintain shaft 23 in stationary position.

From the tab assembling unit each container blank is carried by conveyor belt 2 to pass between pressing rolls 27 (Fig. 3) secured to shafts 28 journaled in frame 1. Thence the blank passes to an adhesive applying device, comprising a glue wheel 51 driven by shaft 52 journaled in reservoir 53 secured to frame 1. In passing over the adhesive applying wheel 51 a stripe of glue is applied to the under surface of connection flap *e* of the container blank (Figs. 9 and 10). Roll 54 rotatably mounted on shaft 55 supported by brackets 56 secured to frame 1 serves to hold the blank in contact with the adhesive applying roll 51 as the blank is conveyed forward.

The blanks are then advanced in spaced relation to the folding unit (Figs. 1 and 2); guide bars 57 supported by frame 1 serve to hold the traveling blanks in contact with the conveyor belt 3 and also to guide the folding operation to creased lines *y*1 and *z*2 (Fig. 7). Folding bars 58 supported by brackets 59 secured to frame 1 serve to fold wall member *a* of the blank (Figs. 9 and 10) against wall member *b*, and also to fold side wall *d* so that the free edge of side walls *d* will contact the adhesively treated surface of flap connection *e*. The blank is then in the condition illustrated by Figure 11. From the folding unit the blanks are advanced to the

delivery belt 60 driven by rolls 61 secured to shafts 62 journaled in brackets 63 which are secured to frame 1.

It will be readily understood, without need of illustration, that any suitable motor may be employed for operating the machine, and that suitable gearing is employed in practice to cause the various rolls and shafts to operate at uniform peripheral speed to effect travel of the blanks through the machine and to operate the various devices which act upon the blanks in sequence. The cut and creased container blanks are fed singly and successively to the conveyor belt which carries the blanks to the several units which operate on the blanks in timed relation. The timing is such that when the machine is in operation different parts of the machine are operating simultaneously on blanks which are spaced on the conveyor belt. In other words, while one part of the machine is performing an operation on one blank other parts of the machine are at the same time performing other operations on other blanks, all of said blanks following one another progressively through the machine and are delivered therefrom as containers in collapsed condition as shown in Figure 11.

While the invention includes the combined instrumentalities above mentioned, I wish it to be understood that I consider the aforesaid means not only combinatively novel, but insofar as I am aware, certain of the devices going to make up such means are new in less combinations than the whole and some capable of individual use, as will be apparent from the description of the machine herein disclosed.

It will be apparent that my improved method and machine are suitable for many purposes other than for applying a patch or tab as illustrated in Figures 7 to 14. The container illustrated by Figures 7 to 15 inclusive, is shown merely for the purpose of illustration, and it should be understood that I do not limit myself to the production of this specific product.

It is to be understood that in practice, suitable mechanisms are provided for adjusting the several units of the machine to operate on blanks of various sizes.

Having now described my invention in one of its embodiments, what I claim is:

1. In a machine for making and affixing reinforcing tabs to sheets of material, a conveyor for advancing sheets singly and successively, a member carrying a web of tab material; a tab forming means comprising a die cutting unit having scoring, punching and web severing devices; means for advancing the tabs singly and successively, a tab applying wheel having prongs on the periphery thereof to engage each tab as it is advanced, means for rotating the wheel to deliver the tabs in superposed position upon the sheets, mechanism within said wheel to release the tab engaging means, and pressing rollers for pressing the tabs against the sheets.

2. In a machine for making and affixing reinforcing tabs to sheets of material, a conveyor for advancing sheets singly and successively, a member carrying a web of tab material; a tab forming mechanism comprising a die cutting unit having scoring, punching and web severing devices; a tab applying wheel having prongs on the periphery thereof to engage each tab as it is advanced, means for delivering the tabs to superposed positions upon the sheets, mechanism within said wheel to release the tab engaging

means, and pressing rollers for pressing the tabs to the sheets.

3. In a container making machine of the class described, a conveyor mechanism, means for applying adhesive to a predetermined area of container blanks, a member carrying a web of reenforcing material, a tab forming unit, means for advancing the prepared tabs singly and successively to a tab applying wheel having prongs at the periphery thereof, mechanism operating to withdraw the prongs from the tabs after the tabs have been registered upon the sheets, pressing rollers for firmly pressing the tabs against the sheets, a roller for applying a stripe of adhesive to an edge of the blank, and means for folding opposite side areas of the blank toward each other.

4. In a box making machine of the class described, a conveyor mechanism, means for applying adhesive to predetermined areas of box blanks, a member carrying a web of reenforcing material, a tab forming unit, means for advancing the tabs singly and successively, a tab applying wheel having prongs on the periphery thereof to engage each tab as it is advanced, mechanism within said wheel operating to release the tab engaging means, pressing rollers for firmly pressing the tabs against the sheets, a roller for applying a stripe of adhesive to an edge of the traveling blank, and means for folding opposite side areas of the blank toward each other.

5. In a container making machine of the class described, a conveyor mechanism, means for applying adhesive to predetermined areas of container blanks, a member carrying a web of tab material; tab forming means comprising a die cutting unit having scoring, punching and web severing means; a tab applying wheel having at the periphery thereof prongs which contact and advance the prepared tabs, mechanism operating within said wheel to withdraw the prongs from engagement with the tabs after the tabs have been positioned on the container blanks, pressing rollers for firmly pressing the tabs to the blanks, a roller for applying a stripe of adhesive to an edge of the traveling blank, and means for folding opposite side areas of the blank toward each other.

6. In a machine for preparing and affixing reinforcing tabs to sheet material, a member carrying a supply of reenforcing tab material; tab forming devices comprising a die cutting unit including a shearing punch, a scoring knife and a tab severing knife; means for advancing prepared tabs singly and successively, a tab applying wheel having prongs at the periphery thereof, means for causing the prongs to dig into a tab, mechanism operating to withdraw the prongs from contact with the tab after the tab has reached the position of register upon a sheet of material, and pressing rollers for pressing the tabs against the sheet material.

7. In a machine for preparing and affixing reinforcing tabs to sheet material, a member carrying a supply of reenforcing tab material; tab forming mechanism comprising a die cutting unit having a shearing punch, a scoring knife and a tab severing knife; a tab applying wheel having at the periphery thereof prongs for engaging a tab and registering it upon sheet material, mechanism operating to withdraw the prongs from contact with the tab, and pressing rollers for pressing the tabs to the sheets.

8. In a machine for making and affixing reinforcing tabs to sheets of material, a member

carrying a web of reinforcing tab material; tab forming means comprising a die cutting unit having scoring, punching and tab severing means; rolls for advancing the tabs singly and successively, a tab applying wheel with prongs on the periphery thereof to engage each tab as it is advanced and for delivering the tabs to superposed position upon the traveling sheets, mechanism to release the tab engaging means, and pressing rollers for pressing the tabs against the sheets.

9. In a box making machine of the class described, a conveyor mechanism, means for applying adhesive to predetermined areas of box

blanks, a member carrying a web of reinforcing material; tab forming means comprising a die cutting unit having scoring, punching and web severing means; rolls for advancing the tabs singly and successively, a tab applying wheel with prongs on the periphery thereof to engage each tab as it is advanced, mechanism operating to release the tab engaging means from contact with the tab, pressing rollers for firmly pressing the tabs to the sheets, a roller for applying a stripe of adhesive to an edge of the traveling blank, and means for folding opposite side areas of the blank toward each other.

MELVIN H. SIDEBOOTHAM.
